UNITED STATES PATENT OFFICE.

CLAUDE E. TRINDER, OF MANLIUS, NEW YORK.

VALVE.

1,080,791.

Specification of Letters Patent.

Patented Dec. 9, 1913.

Application filed February 24, 1912. Serial No. 679,564.

To all whom it may concern:

Be it known that I, CLAUDE E. TRINDER, of Manlius, in the county of Onondaga and State of New York, have invented a certain new and useful Valve, of which the following is a specification.

My invention has for its object the production of a valve which is particularly simple in construction, economical in manufacture and highly efficient and durable in use; and it consists in the combinations and constructions hereinafter set forth and claimed.

In describing this invention reference is had to the accompanying drawing in which like characters designate corresponding parts in all the views.

Figure 1 is a longitudinal sectional view of a preferable form of my invention. Fig. 2 is a plan of the spring embodied in the form of valve illustrated in Fig. 1. Figs. 3 and 4 are respectively, a plan and a sectional view of a slightly different form of handle and spring and contiguous parts, from that shown in Fig. 1. Figs. 5 and 6 are views similar to Figs. 3 and 4 of additional modified forms of handle and spring.

1 is the body of the casing of the valve, said body being formed with a valve seat 2, a threaded opening 3 alined with the valve seat 2, and with inlet and outlet couplings 4, 5.

6 is a bonnet forming part of the casing, the bonnet extending into the opening 3 and being formed with inner and outer nipples 7, 8 having axially alined bores of the same diameter, these bores communicating at their inner ends with a chamber 9 formed in the main central portion 10 of the bonnet member, from which portion 10 the nipples project. Preferably the inner face of the nipple 7 and the periphery of the nipple 8 are threaded.

The bonnet is formed substantially symmetrical with respect to a plane, indicated by the line "X—X" Fig. 1, extending transversely through the main portion 10 thereof midway between the ends of the bonnet, and preferably the main portion 10 is formed with a central annular circumferential flange 11 extending along such plane and with a threaded portion 12 below the flange for turning into the threaded opening 3, and with a portion 13 above the flange, and with a portion 13 above the flange, the wrench shaped to form a wrench hold, the wrench hold 13 being usually angular, as hexagonal, in form. Owing to the flange 11, which laps

the edge of the body 1 around the opening 3, roughening of such edge with a wrench is prevented. Owing to the fact that the bonnet is symmetrical, as set forth, and that the bores thereof are of equal diameter, the cost of manufacturing and machining the bonnet is reduced to a minimum.

14 is a neck forming part of the valve casing, the neck having a lengthwise passage alined with the valve seat 2 and the opening 3, and an internally threaded cupped portion 15 of enlarged diameter, at its lower end for turning on the externally threaded nipple 8 of the bonnet, the neck also having a portion 16 shaped to form a wrench hold and located above the cup 15. The bottom of the cup portion 15 partly closes the upper end of the opening 3 and forms an annular bearing face for the ring or washer 24, presently described, and the inclosing wall of said portion 15 constitutes a depending internally threaded flange at the bottom of the neck 14.

17 is a valve head coacting with, and movable toward and from, the valve seat 2, and 18 is a carrier for such valve head, the carrier being here shown as externally threaded and turning in the inner nipple 7 of the bonnet 6. The valve head 17 is suitably secured to the carrier 18.

19 is a stem for operating the valve head, the stem extending upwardly through the bonnet 6 and neck 14 beyond the end of the neck and being non-movable endwisely in its normal operation but having a limited endwise adjusting movement for a purpose to be explained. The lower end of the stem is formed non-circular and slidably fits the non-circular entrance 20 of a socket formed in the carrier 18. Said stem is formed as a single unit, that is, it is not formed of sections having relative movement. The lower portion 21 of said socket of the carrier is preferably formed of larger diameter than the upper end thereof which slidably fits the stem 19. The enlarged portion 21 prevents binding of the carrier 18 and stem 19 in case the carrier is tilted slightly out of axial alinement, as when the external threads of the carrier do not take evenly into the threads of the nipple 7; and for additionally providing for the tilting tendency of the carrier 18 without binding, the upper end surface of the carrier 18 is rounded as 22 around the upper end of the entrance 20. The entrance 20 and the enlargement

21 open through opposite ends of the carrier and are formed with a core during the casting of the carrier and therefore the formation of the enlargement does not add to the 5 cost of the carrier. The stem is also shown as provided with means for engaging the smooth bore of the outer nipple 8, this means being shown as an integral annular flange 23 one face of which is opposed to the inner 10 end face of the cup 15, and a member, as a ring or washer 24 for rendering the casing non-leakable, is interposed between the opposing surfaces of the flange 23 and the bottom of the cup 15, this member being 15 formed of suitable metallic or composition material and being formed with annular grooves on its opposite faces for receiving annular beads 25 and 26 provided on said opposing faces of the flange 23 and the 20 bottom of the cup 15. The washer snugly fits the bore of the nipple 8 and tends to hold the stem from lateral movement, the grooves and beads 25, 26 also tending to hold the stem from lateral movement. The 25 internal bore of the nipple 8 is smooth so that the washer can be made to fit the bore. If the nipple were provided with internal threads, the washer would have to be passed over said threads when being placed in position and such threads would pare off portions of the periphery of the washer so that it would not fit tightly and perform its function most efficiently.

27 is an operating element here shown as 30 a handle mounted on the outer end of the stem 19, the handle being here illustrated as provided with a cup member 28 on its underside, which receives and slides or moves relatively to the upper enlarged end 29 of the 35 neck 14, the cup member being formed with a non-circular axial passage in its bottom which slidably receives a non-circular portion 30 at the upper end of the stem 19 and serves to transmit the motion of the handle 40 27 to the stem. The cup is suitably secured to the stem, and in order to lock the cup and handle together so that the rotation of the handle is transferred to the cup, the cup is formed with projections 31 at intervals 45 which enter corresponding sockets in the handle 27. As here shown the cup is countersunk in the lower face of the handle.

32 is a member as a ring or washer similar to the washer 24, the washer 32 being 50 interposed between and engaging the upper or outer end of the neck 14 and the bottom of the cup 28, and the periphery of the washer engaging a part of the inner face of said cup. The opposing faces of the end 55 60 edge of the neck 14 and of the washer are formed respectively with a bead and a groove similar to the beads 25 and 26 of the flange 23 and the cup 15 and the grooves of the washer 24. This washer 32 serves as 65 an anti-friction member during the turning

of the handle 27 and prevents lateral movement of the handle and stem. To those skilled in the art, it will be understood that the faces of the stem 19 and its handle which turn against the opposing surfaces of the bonnet and the neck do not tightly fit said 70 opposing surfaces, and that the inner and the outer surfaces of the washers 24 and 32 do tightly fit the surfaces engaged therewith, and that thus to a limited extent the washers prevent lateral movement of the 75 handle and the stem.

33 is a spring for adjusting the stem end-wisely for the purpose of clamping the washer 24 against the bottom of the cup 15 and thereby rendering the valve un leakable and for also clamping the washer 32 between the opposing surfaces of the neck 14 and the cup 28, said spring being located outside of the casing and being preferably carried by the handle and having marginal portions thereof seated on the handle and the intermediate portion thereof connected to the stem. Preferably the spring is in the form 85 of a sheet metal disk, Figs. 1 and 2, mounted 90 on the outer face of the handle 27 and having its margin engaging with the seat 34 concentric with the stem 19 and having a central portion connected to the stem. As here shown the central portion is connected 95 to the stem by a clamping member, as a screw 35, passing through an opening 36 at the center of the disk 33 and threading into the stem 19. Obviously as the screw 35 is turned into the stem 19, the spring 33 is tensioned so that it tends to move the stem 19 100 axially outwardly.

As seen in Figs. 3, 4, 5 and 6, the spring instead of being in the form of a disk and forming a complete cover for the central portion of the handle 27, may be in the form of a disk cut away to form radially extending arms 37, the ends of which engage spring seats on the handle, the seats being spaced apart from each other and 110 from the axis of the stem 19.

In Figs. 3 and 4, the handle 27 instead of being formed solid, is shown in the form of a wheel having spokes 38, the arms of the spring overlying such spokes.

In Figs. 5 and 6, the spring is shown as in the form of a strip of sheet metal, and is applied to a lever-handle connected to the stem, the lever having a pointer 39 movable over a dial 40 which indicates the position 115 120 of the valve head with respect to the valve seat, that is, whether the valve is open or closed or to what extent it is open.

In Figs. 1 to 4 inclusive, the spring is shown as concaved out of a plane when tensioned, and in Figs. 5 and 6, such spring is normally convex and is flattened as it is tensioned.

This invention is particularly advantageous in that the parts thereof can be 130

cheaply and quickly manufactured and in that it is non-leakable and contains no packing material which needs to be replaced, and further in that the spring is located entirely outside of the body of the casing and therefore is not affected by the heat of a heating medium.

What I claim is:

1. In a valve, a casing including a body formed with a valve seat, the casing comprising a neck having a passage aligned with the valve seat, the neck also having oppositely facing bearing surfaces, a valve head coacting with the valve seat, a stem consisting of a single member for coöperating with the valve head and extending through the passage, spaced apart bearing rings encircling the stem and coacting with the stem and said oppositely facing surfaces, the periphery of the lower bearing ring also coacting with the casing, a part mounted on the outer end of the stem and connected thereto to permit slight endwise relative movement of said part and the stem, said part having a bearing upon the end and the periphery of the upper bearing ring, and a spring mounted on said part and connected to the stem to pull upwardly on the stem, and clamp the bearing rings against said oppositely facing surfaces, substantially as and for the purpose described.

2. In a valve, a casing provided with a valve seat and a neck, a valve head movable toward and from the valve seat, a stem for operating the valve head, the stem extending lengthwise of the neck and projecting beyond the outer end of the same, a member mounted on the outer end of the stem to turn the same, said member being movable relatively to the neck with the stem and having a cupped portion encircling the upper end of the stem, the stem and said member having slight relative axial movement, a ring fitting within said cupped portion and interposed between the bottom thereof and the upper end of the neck, an end face of the ring and one of the faces between which the same is interposed, having interfitting means whereby the ring is held centered during the turning movement of said member and the stem, said ring holding said member and the stem in axial alinement and preventing lateral movement thereof relatively to the neck, and a spring between said member and the stem tending to move the same in opposite directions, substantially as and for the purpose specified.

3. In a valve, a casing provided with a valve seat, and a neck, a valve head movable toward and from the valve seat, a stem for operating the valve head, the stem extending lengthwise of the neck and projecting beyond the outer end of the same, a member mounted on the outer end of the stem to turn

the same, said member being movable relatively to the neck with the stem and having a cupped portion encircling the upper end of the stem, and a ring fitting within said cupped portion and interposed between the bottom thereof and the upper end of the neck, an end face of the ring and one of the faces between which the same is interposed having interfitting means whereby the ring is held centered during the turning movement of said member and the stem, said ring holding said member and the stem in axial alinement and preventing lateral movement thereof relatively to the neck, substantially as and for the purpose described.

4. In a valve, a casing provided with a valve seat, and a neck, a valve head movable toward and from the valve seat, a stem for operating the valve head, the stem extending lengthwise of the neck and projecting beyond the outer end of the same, a member mounted on the outer end of the stem to turn the same, said member having a cupped portion encircling the upper end of the stem, the lower part of said cupped portion being movable relatively to the periphery of the contiguous part of the neck, and a ring within said cupped portion between the bottom thereof and the upper end of the neck, the periphery of the ring engaging a part of the inner face of the cupped portion, and the end faces of the ring engaging the bottom of said cupped portion, and the upper end of the neck, substantially as and for the purpose specified.

5. In a valve, a casing provided with a valve seat, and a neck, a valve head movable toward and from the valve seat, a stem for operating the valve head, the stem extending lengthwise of the neck and projecting beyond the outer end of the same, a member mounted on the outer end of the stem to turn the same, said member having a cupped portion encircling the upper end of the stem, the lower part of said cupped portion being movable relatively to the periphery of the contiguous part of the neck, and a ring within said cupped portion between the bottom thereof and the upper end of the neck, the periphery of the ring engaging a part of the inner face of the cupped portion, and the end faces of the ring engaging the bottom of said cupped portion, and the upper end of the neck, an end face of the ring and the face engaged therewith being formed with interfitting means for holding the stem centered during the turning movement thereof and preventing lateral movement of said stem relatively to the neck, substantially as and for the purpose set forth.

6. In a valve, a casing comprising a body formed with a valve seat, and a neck, a valve head movable toward and from the valve seat, a stem for operating the valve head, the stem extending lengthwise of the neck and

- projecting beyond the outer end of the same, a member mounted on the outer end of the stem to turn the same, the stem and said member having relative axial movement, 5 and said member having a cupped portion encircling the upper end of the stem, and a ring fitting within said cupped portion and interposed between the bottom thereof and the upper end of the neck, the neck and said 10 ring having interfitting means whereby the ring is held centered during the turning movement of said member and the stem, said ring holding said member and the stem in axial alinement and preventing lateral movement thereof relatively to the neck, substantially as and for the purpose specified. 15
7. In a valve, a casing provided with a valve seat, and a neck, a valve head movable toward and from the valve seat, a stem for operating the valve head, the stem extending lengthwise of the neck and projecting beyond the outer end of the same, a member mounted on the outer end of the stem to 20 turn the same, the stem and said member having relative axial movement, and said member having a cupped portion encircling the upper end of the stem, the lower part of said cupped portion encircling the periphery of the upper end of the neck and being 25 movable relatively thereto in two directions, and a ring within said cupped portion between the bottom thereof and the upper end of the neck, the periphery of the ring engaging a part of the inner face of the 30 cupped portion, and the end faces of the ring engaging the bottom of said cupped portion, and the upper end of the neck, substantially as and for the purpose described. 35
8. In a valve, a casing provided with a valve seat, an opening alined with the valve seat, and a neck detachable from the portion of the casing inclosing said opening and having a lengthwise passage alined with the 40 valve seat and the opening, and having an annular bearing face partly closing the upper end of said opening, a valve head movable toward and from the valve seat, a revoluble stem for operating the valve head, the 45 stem extending through the opening and the passage and having an annular projecting shoulder spaced apart from the annular bearing face and opposed thereto, and a ring having its periphery engaged with the 50 inner face of the wall of the casing inclosing said opening, and its end faces engaged with said annular face and the face of the annular shoulder opposed to said annular face, an end face of the ring and the face engaged 55 therewith being formed with interfitting means for holding the stem centered during the turning movement thereof and preventing lateral movement of said stem relatively to the neck, substantially as and for the purpose described. 60
- 65

9. In a valve, a casing provided with a valve seat, a nipple having its bore alined with the valve seat and its periphery threaded, and a neck having at its bottom an internally threaded depending flange coacting with the threaded periphery of the nipple, and also having an annular bearing face partly closing the upper end of the bore of the nipple, a valve head movable toward and from the valve seat, a revoluble stem for operating the valve head, the stem extending through the nipple and the passage and having an annular projecting shoulder spaced apart from the annular bearing face and opposed thereto and having its periphery engaged with the inner face of the wall of the nipple surrounding the bore of said nipple, and a ring having its periphery engaged with the inner face of said wall surrounding the bore of the nipple and its end faces engaged with said annular face and the face of the annular shoulder opposed to said annular face, substantially as and for the purpose set forth. 70
- 75
10. In a valve, a casing provided with a valve seat, a nipple having its bore alined with the valve seat and its periphery threaded, and a neck having at its bottom an internally threaded depending flange coacting with the threaded periphery of the nipple, and also having an annular bearing face partly closing the upper end of the bore of the nipple, a valve head movable toward and from the valve seat, a revoluble stem for operating the valve head, the stem extending through the nipple and the passage and having an annular projecting shoulder spaced apart from the annular bearing face and opposed thereto, and having its periphery engaged with the inner face of the wall of the nipple surrounding the bore of said nipple, and a ring having its periphery engaged with the inner face of said wall surrounding the bore of the nipple and its end faces engaged with said annular face and the face of the annular shoulder opposed to said annular face, substantially as and for the purpose set forth. 80

- having an annular projecting shoulder spaced apart from the annular bearing face and opposed thereto, a member mounted on the outer end of the stem to turn the same, said member being movable relatively to the neck with the stem and having a cupped portion encircling the upper end of the stem, a ring fitting within said cupped portion and interposed between the bottom thereof and the upper end of the neck, and a ring having its periphery engaged with the inner face of the wall of the casing inclosing said opening and its end faces engaged with said annular face and the face of the annular shoulder opposed to said annular face, substantially as and for the purpose specified.
12. In a valve, a casing provided with a valve seat, a nipple having its bore alined with the valve seat and its periphery threaded, a neck having an internally threaded depending flange coacting with the threaded periphery of the nipple and also having an annular bearing face partly closing the upper end of the bore of the nipple, a valve head movable toward and from the valve seat, a stem for operating the valve head, the stem extending through the nipple and the passage beyond the upper end of the neck and having an annular projecting shoulder spaced apart from the annular bearing face and opposed thereto, and having its periphery engaged with the inner face of the wall of the nipple surrounding the bore of said nipple, a member mounted on the outer end of the stem to turn the same, said member having a cupped portion encircling the upper end of the stem, the lower part of said cupped portion engaging the periphery of the contiguous portion of the neck, a ring within said cupped portion between the bottom thereof and the upper end of the neck, the periphery of the ring engaging a part of the inner face of the cupped portion, and the end faces of the ring engaging the bottom of said cupped portion and the upper end of the neck, and a ring having its periphery engaged with the inner face of said wall surrounding the bore of the nipple, and its end faces engaged with said annular face and the face of the annular shoulder opposed to said annular face, substantially as and for the purpose set forth.
13. In a valve, a casing having a valve seat, an opening alined with the valve seat, the casing also comprising a neck having a passage alined with the valve seat and the opening, a valve head movable toward and from the valve seat, a stem for operating the valve head extending through said opening and passage and projecting beyond the outer end of the neck, the stem having an annular shoulder located within the casing and opposed to an inner end face of said neck around the passage of the neck, a member mounted on the outer end of the stem
- and having a cupped portion inclosing the outer end of the neck, a ring fitting within said cupped portion and interposed between the bottom thereof and the outer end face of the neck, the neck and the ring having interfitting means for holding the ring centered relatively to the neck, said ring thereby holding the stem in axial alinement with the neck and preventing lateral movement thereof, and a ring located between said annular shoulder and said inner end face of the neck, said
- 5 10 15 20 25 30 35 40 45 50 55 60 65 70 75 80 85 90 95 100 105 110 115 120 125 130

shoulder, the neck and the latter ring having interfitting means for holding the latter ring centered whereby the stem is held from lateral movement, and a spring located outside of the casing and connected to the stem to move the same outwardly, substantially as and for the purpose set forth.

In testimony whereof, I have hereunto

signed my name in the presence of two attesting witnesses, at Syracuse, in the county 10 of Onondaga, and State of New York, this 29th day of January 1911.

CLAUDE E. TRINDER.

Witnesses:

S. DAVIS,
L. M. DAVIS.
